UNITED STATES PATENT OFFICE.

WILLIAM H. JACOBY, OF MINNEAPOLIS, MINNESOTA.

BILLIARD-CUE-TIP FASTENER.

SPECIFICATION forming part of Letters Patent No. 452,014, dated May 12, 1891.

Application filed October 15, 1890. Serial No. 368,207. (No model.)

To all whom it may concern:

Be it known that I, WILLIAM H. JACOBY, of Minneapolis, in the county of Hennepin and State of Minnesota, have invented certain Im-
5 provements in Billiard-Cue-Tip Fasteners, of which the following is a specification.

My invention relates to means for securing the tip on a billiard-cue and holding it in place while the glue or other material used
10 as an adhesive sets or becomes drawn and stable; and the invention consists, generally, in the construction and combination herein-
after described, and particularly pointed out in the claims.

15 In the accompanying drawings, forming a part of this specification, Figure 1 is a side elevation of my improved device. Fig. 2 is a transverse section of the same.

In the views, 2 represents the main frame
20 or casting, having the three depending projections 3, 4, and 5. The projections 3 and 4 are provided with the curved feet 7 and 8, respectively, to receive the cue 9. The projection 3 is constructed, preferably, longer than
25 the projection 4, so as to elevate the portion of the frame 2 farthest from the end of the cue. The projection 5 is enlarged at its lower end 16 and provided with a hole admitting the stem 11, the head 12 of which is riveted
30 to prevent its being removed from the hole or opening in the frame 2. The other end of the stem 11 is provided with an enlarged cap 13, hollowed out to receive the tip 6, and forming a shoulder 14 for the spiral spring 15
35 to press against, which is wound around the stem 11 and has for its other bearing the enlarged portion 16 and the arm 5.

Upon the side of the frame 2, and preferably constructed integrally therewith, is a
40 projecting shelf or flange 18 parallel to the general direction of the frame 2 and obliquely to the longitudinal axis of the billiard-cue.

Loosely embracing the frame 2 is the clamp 20, the lower portion 21 being curved to form
45 a suitable support for and to grasp the cue. In the projection 23 is provided a screw-
threaded opening adapted to receive the set-
screw 25, which is preferably arranged to press
perpendicularly against the shelf or flange
50 18, so that when it is screwed down through

the projection 23 it presses upward against the cue by means of the curved support 21 holding the cue firmly against the feet 7 and 8 of the projections 3 and 4.

In operating this device the set-screw 25 is 55 first loosened so as to readily admit the insertion of the cue 9 between the curved portions 7 and 8 and the support 21 of the clamp 20. The tip 6, being first treated with the glue or other adhesive, is placed on the end 60 of the cue 9, when by holding the cue 9 in one hand, preferably letting the other end of the cue rest on the floor or ground and pressing the clamp downward with the other, the requisite pressure is brought to bear on the 65 tip by the spring 15 pressing out the superfluous adhesive material, and the open construction of the device permits the tip to be satisfactorily adjusted on the end of the cue. When the desired tension is attained, the cue 70 is secured firmly in place by means of the set-screw 25, which on being screwed against the flange 18 draws the support 21 on the under side of the cue 9 upward, clamping the cue 9 firmly against the projecting 75 curved portions 7 and 8 of the frame 2. To release the cue the set-screw 25 is loosened and the clamp forced upward on the inclosed portion of the frame 2. This operation throws the clamp 21 out of contact with the cue, 80 which may be readily removed.

I claim as my invention—

1. The combination, with a billiard-cue and the tip, of the frame 2, having the projections 3 and 4 adapted to receive the cue, the projection 5, carrying the stem 11 and spiral spring 15, the projecting flange 18, clamp 20, and the set-screw 25, substantially as described, and for the purpose set forth. 85

2. The combination of the frame 2, projections 3, 4, and 5, stem 11, spiral spring 15, clamp 20, having the curved support 21, flange 18, and set-screw 25, combined and constructed substantially as described, and for the purpose specified. 90

3. The combination of the frame 2, having the projections 3, 4, and 5 and the inclined flange 18, constructed integrally therewith, the projections 3 and 4 having the curved lower portions 7 and 8, respectively, to re- 100

ceive the cue, and the projection 5 having the enlarged lower portion provided with an opening, the spring 15, stem 11, clamp 20, having the curved support 21 and adapted 5 to embrace the frame 2 with its upper portion, and the set-screw 25, substantially as described.

In testimony whereof I have hereunto set my hand this 24th day of March, 1890.

WILLIAM H. JACOBY.

In presence of—

A. M. GASKILL,
P. C. PAUL.
